(57) **CLAIM**

The ornamental design for a garden tool, as shown and described.

DESCRIPTION

FIG. 1 is a perspective view of a garden tool showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of the selected portion 9 shown in FIG. 1;

FIG. 10 is a partial enlarged view of the selected portion 10 shown in FIG. 1;

FIG. 11 is a partial enlarged view of the selected portion 11 shown in FIG. 2; and,

FIG. 12 is a perspective view of the garden tool, shown with environment.

The broken line showing of a garden tool is for the purpose of illustrating portions of the article and forms no part of the claimed design. The broken line showing of environment in FIG. 12 is for the purpose of illustrating environmental structure and forms no part of the claimed design.

1 Claim, 12 Drawing Sheets
